UNITED STATES PATENT OFFICE

HAROLD EDGAR YARROW, OF GLASGOW, SCOTLAND

PULVERIZED FUEL BURNER

Application filed June 13, 1929, Serial No. 370,569, and in Great Britain August 24, 1928.

One object of the present invention is to obtain as short a flame as possible consistent with efficient combustion in a pulverized fuel burner, so that the size of the combustion chamber can be kept within comparatively small limits.

To ensure this result it is necessary to have a zone of high temperature where the powdered fuel first enters the furnace, so that the hydrocarbons in the fuel will be immediately set free and at the same time the temperature of the residual particles of carbon will be raised to such an extent that these particles will immediately combine with the oxygen supplied for their combustion.

According to the present invention this high temperature zone with its consequential advantages is obtained by so constructing the burner that some of the ignited fuel will be drawn back towards and into the burner, thereby heating one or more of the entering fuel mixture constituents by direct contact.

This is effected by introducing a Venturi constriction and nozzle in an annular passage through which one or more of the fuel mixture constituents pass to the combustion space, thereby reducing the pressure locally and inducing a backward flow of ignited fuel towards and through the Venturi nozzle into the entering fuel constituent.

This and other features constituting the present invention are more specifically described with reference to the accompanying drawing, wherein Fig. 1 is a central longitudinal section of a burner embodying the invention, and Fig. 2 is an end elevation thereof.

In the burner shown the pulverized fuel and primary air supply enter the outer tube H through the passage C, while the secondary air supply is derived from an air box or trunk B formed between the transverse plates R. Air from the air box or trunk B is supplied to the tube H through a passage between vanes D mounted in said passage at an

inclination to the radii of the tube H (by which it is given a gyratory motion) and thence to the annular inlet S leading to the combustion chamber.

The annular passage M between the outer tube H and the inner tube E of the burner is formed with a Venturi constriction at an intermediate point, and at this point the inner burner tube E is divided transversely and has its adjacent ends shaped to form an annular constricted nozzle N (or alternatively has nozzles formed in its wall) leading into the Venturi constriction in the passage M. This annular nozzle N, or an equivalent plurality of nozzles, is preferably directed somewhat towards the furnace end of the passage M.

The delivery or furnace end of the inner tube E is preferably fitted with a sliding extension piece G, which can be projected into the furnace to a greater or less extent, as by means of a rod Q which is suitably supported in the wall of the passage C and in the plate O which closes the outer end of the tube E. This plate may be a flat plate as shown in full lines in Fig. 1, or it may be of other suitable shape.

The reduction in pressure within the burner, due to the Venturi constriction, induces a backward flow from the combustion space of hot gases which pass through the nozzle N and mingle directly with the fuel constituent or constituents which enter the burner through the passage C, so that the latter are heated to a comparatively high temperature before their delivery to the furnace through the annular discharge aperture S. The adjacent edges of the two parts of the tube E are preferably made bulbous and shaped so as to form between them a converging nozzle N, as stated above.

The result of this construction is that the fuel mixture constituent or constituents which enter through the nozzle C are delivered to the combustion space of the furnace at

a high temperature and consequently there will be a zone of high temperature within the furnace due to the immediate and complete combustion of the fuel.

5 Moreover, since the secondary air supply has a rapid whirling motion at the point where it meets the pulverized fuel stream, namely in front of the annular discharge opening S, the secondary air and the fuel stream are intimately mixed and owing to their rapid gyratory motion they tend to form a conical vortex of rapidly increasing area, with the result that there is a reduction of pressure at the edge T of the sleeve U 10 which projects into the combustion space and encircles the discharge end of the burner. Consequently not only is the inner part of the expanding vortex of burning fuel turned back on itself into the mouth of the tube G, but 15 the outer part of the expanding vortex is turned back on itself around the rear edge of the sleeve U, so that the fuel is exposed to direct contact with the flame as it enters the furnace. Complete gasification of the hydro- 20 carbons is thereby obtained, and the carbon particles are also raised to a temperature at which they immediately ignite, thereby making the resulting flame short and intense.

It may be desirable to give a gyratory motion to the fuel constituent or constituents which enter the burner through the inlet pipe C prior to their discharge from the end of the passage M, and this may be done by a convenient arrangement of inclined or helical 35 vanes situated at or near the discharge end of the passage M.

Having thus described the nature of the said invention and the best means I know of carrying the same into practical effect, I 40 claim:—

1. A pulverized fuel burner comprising a duct to convey a fuel constituent to a furnace, a second duct disposed within the first duct closed at one end and leading at the other 45 end to the furnace, a Venturi constriction formed by the inner and outer surfaces respectively of the first and second ducts, the second duct having in its wall an aperture substantially in the transverse plane of the 50 said Venturi constriction.

2. A pulverized fuel burner comprising a duct to convey pulverized fuel and air to a furnace, a second duct situated within the first duct and closed at one end and leading 55 at the other end into the furnace, a Venturi constriction formed between the inner and outer surfaces respectively of the said first and second ducts, said second duct having in its wall an aperture substantially in the trans- 60 verse plane of the said Venturi constriction.

3. A pulverized fuel burner according to claim 2, comprising an air trunk surrounding the fuel conveying conduct and passages leading from said air trunk to the said duct near 65 the discharge end thereof.

4. A pulverized fuel burner according to claim 2, comprising an air trunk surrounding the fuel conveying duct, passages leading from said air trunk to the said duct near the discharge end thereof, and vanes in said passages inclined to the radii of said duct adapted to impart a whirling motion to the air passing therethrough.

In testimony whereof I have signed my name to this specification.

HAROLD EDGAR YARROW.
